United States Patent

Des. 237,470
Patented Nov. 4, 1975

237,470

CLOCK

John A. Hubley, Jr., 413 S. Cherry St.,
Lititz, Pa. 17543

Filed Nov. 21, 1973, Ser No. 417,762

Term of patent 14 years

Int. Cl. D10—01

U.S. Cl. D10—28

Fig. 1

Fig. 2

Fig. 3

FIG. 1 is a front elevational view of a clock showing my new design;

FIG. 2 is a right side elevational view thereof, the left side being a mirror image thereto; and

FIG. 3 is a bottom plan view thereof.

The rear of the clock, not shown, is substantially plain and unornamented.

I claim:

The ornamental design for a clock, substantially as shown and described.
